UNITED STATES PATENT OFFICE

117,862

DESIGN FOR A CUSHION

Edward H. Bauer, Los Angeles, Calif.

Application September 13, 1939, Serial No. 87,191

Term of patent 7 years

To all whom it may concern:

Be it known that I, Edward H. Bauer, a citizen of the United States, residing at Los Angeles, in the county of Los Angeles, State of California, have invented a new, original, and ornamental Design for a Cushion, of which the following is a specification, reference being had to the accompanying drawing, forming part thereof.

In the drawing—

Fig. 1 is a perspective view of one side of a cushion embodying the design of my invention;

Fig. 2 is a perspective view of the opposite side of the cushion of Fig. 1.

I claim:

The ornamental design for a cushion, as shown.

EDWARD H. BAUER.
